MACHINE FOR PRINTING ON CYLINDRICAL
GLASSWARE

Luigi Marzocchi, Milan, Italy

Application December 26, 1939, Serial No. 311,019

4 Claims. (Cl. 101—40)

The present application is a continuation in part of applicant's copending application Serial No. 271,608, filed May 3, 1939, and relates to a machine for printing on cylindrical glass vials. More specifically the invention pertains to mechanism for feeding glass vials or ampoules to the printing roll, operating the printing mechanism in timed relation to the feeding means, and finally conveying the glassware away from the printing roll.

One of the objects of the invention is to feed and position the glassware accurately with respect to the roll, the feeding and passage of the ware being intermittent.

Another object of the invention is to provide means for urging the ware into engagement with the printing roll, said means being designed to obviate smearing and permit transfer of the printed design to a maximum surface of the ware.

A further object of the invention is to provide movable trays in which the ware is deposited after the printing operation, together with intermittently actuated conveying means for moving the trays.

Still another object of the invention is the provision of perforate curved bottoms for the trays to reduce the area of contact between the ware and the tray and provide for the passage of air through the tray bottom to expedite drying of the printed design.

Other objects will be apparent from the following description of the invention taken in connection with the accompanying drawings of a preferred form of the invention in which—

Fig. 1 is a front elevation of the machine;

Fig. 2 is a fragmentary elevation, partly in section, of the feeding, printing and conveying mechanism;

Fig. 3 is a section taken on line 3—3 of Fig. 2;

Fig. 4 is a section taken on line 4—4 of Fig. 2;

Fig. 5 is a plan view of the conveyor, certain parts thereof being shown in section as indicated by the section line 5—5;

Fig. 6 is a fragmentary plan view of one of the trays employed in connection with the conveyor;

Fig. 7 is a fragmentary front elevation, partly in section, of the feeding device and a platen for urging the ware into engagement with the printing roll;

Fig. 8 is a perspective view of the platen and its actuating arm;

Fig. 9 is a section taken on line 9—9 of Fig. 2;

Fig. 10 is a section of the means for conveying the trays taken on line 10—10 of Fig. 5;

Fig. 11 is a transverse section taken through the platen, the same being shown in engaging relation with a glass vial;

Fig. 12 is a section taken on line 12—12 of Fig. 5;

Figs. 13 and 14 are transverse and longitudinal sections respectively of one means for adjusting the ink transfer rolls.

In the drawings it will be seen that the printing mechanism and conveyor are mounted on a suitable base or frame 20 which also supports an electric motor 21. Fast on shaft 22 is a pulley 15 or sprocket 23 connected to motor 21 by a belt or chain 24. Worm 25 on shaft 22 drives worm wheel 25' fast on shaft 26. Also secured to shaft 26 are cams 27, 28, 29, and gear 31, the purpose of which will be explained hereinafter.

20 The printing mechanism consists of a pair of ink reservoirs 32, 33, movable transfer rolls 34, 35, 36, 37, fixed transfer rolls 38, 39, 41, 42, impression rolls 43, 44, having appropriate dies 45, 46 thereon, and printing roll 47. Rolls 34, 25 35, 36 and 37 are mounted on stub shafts 48, 49, 51, 52 on the arms 53, 54 of an oscillatable yoke 55 fixed to shaft 56 which is journaled in housing 57. The movable rolls are all freely rotatable on the stub shafts. On the other hand, rolls 38, 39 are fixed on shafts 58, 59, each having a toothed ratchet wheel 61 thereon adapted to be intermittently rotated by suitable pawls as indicated at 62. Rolls 41, 42 are likewise fixed to shafts 63, 64 having secured thereto pinions 65, 66 meshing with gear 31 and adapted to be continuously rotated thereby. Printing roll 47 is secured to shaft 67 to which is also keyed or otherwise fixed star wheel 68, which is rotated by pin 68'.

25 As will be seen from Fig. 4, arm 69 is connected to shaft 56 preferably through a suitable yieldable connection. Arm 69 carries a follower 71 adapted to ride on cam 27 so that the yoke will be oscillated in predetermined timed relation to intermittent rotation of the printing roll. Spring 72 tends to urge the follower toward the cam. Thus it will be apparent that rolls 34, 35 first engage rolls 38, 39, after which the yoke swings to its other extreme so that rolls 34, 35 transfer ink to stationary rolls 41, 42. In the position of the yoke rolls 51, 52 engage rolls 41, 42, while at the other extreme of oscillation they transfer ink to the die rolls 45, 46. It is to be understood that rolls 34, 35, 36, 37 and printing roll 47 are

covered with a yieldable sleeve of gelatin, rubber or similar material.

The film of ink taken up by rolls 38, 39 is controlled by gates 73, 74 of spring metal, the position of the edges of which may be adjusted by turning screws 75, 76. Suitable spreading rolls 77, 78 are mounted on shafts 79, 80, the latter being reciprocable to move the spreading rolls axially with respect to the stationary rolls. The means reciprocating the spreaders includes a yoke 81 to which shafts 79, 80 are connected, cam 29 and follower 82. Springs 83, 84 tend to urge the follower against its cam.

It is to be noted that the rolls 43, 44 are rotated by means of pinions 85 secured to these rolls and meshing with gear 86 secured to roll 47. The pitch circles of the pinions and gear correspond to the diameters of their respective rolls, the gear ratio being 4 to 1. Hence, with each quarter turn of the roll 47 the die rolls turn through one complete revolution, thus making it possible for four transfers to be effected with each full revolution of roll 47. It is also to be noted that each of the die rolls 43, 44 has associated therewith a friction disc 87 having a diameter commensurate with that of the printing surface of the die, these friction discs engaging similar friction discs 88 on rolls 36, 37. Obviously, when the die rolls are rotated during engagement of the friction discs, the rolls 36, 37 will be driven by the die rolls. It is to be understood that the roll carrying yoke 55 is swung to the left (Fig. 2) and the rolls 36, 37 are in engagement with the dies at that period when roll 47 is turning through a quarter revolution.

While the mechanism so far described is designed for two color printing, it is obvious that the arrangement is such that only one color may be printed merely by removing one of the ink reservoirs.

The means for feeding vials to the printing mechanism consists chiefly of a suitable arrangement of gates which release the vials one at a time and means for urging and rolling the vials over the printing roll. For brevity's sake the urging and rolling arm 91 will be referred to hereinafter as a platen. Vials, indicated at 92, are placed on an inclined shelf 93 having side guides 94, 95, the positions of which may be adjusted laterally by screws 96 and nut 97. In this way the vials are accurately centered on the shelf and fed to the printing roll in such a manner that the design will be transferred to the same relative position on each vial. The means for releasing the vials one by one comprises a pair of pivoted gates 98, 99, so actuated that their oscillations are opposite each other. This movement is obtained by securing the gates to shafts on which are pinions 101, 102 meshing with each other so that as one rotates clockwise the other turns in an anti-clockwise direction and vice versa. Pivoted to gate 98 is a connecting rod 103 passing through an aperture 103' in extension 104 of oscillatable lever 105 pivoted at 106 to a fixed standard 107. To the upper end of the connecting rod is threaded a nut 108 between which and washer 109 and surrounding the upper end of the connecting rod is spring 111. Lever 105 is connected by link 112 with arm 113, the latter being mounted for oscillation on shaft 114 and having a rigid connection with rocker arm 115 carrying cam follower 116 thereon. The follower is urged into engagement with cam 28 by a spring 117. It is evident that cam 28 oscillates arm 113 which in

turn oscillates lever 105 raising and lowering rod 103 and the gate 98 attached thereto. At the same time, because of the gear connection between gates 98 and 99, gate 99 is also raised and lowered but in a direction opposite that of gate 98. The depending fingers of the gates are spaced a distance slightly less than the diameter of a vial. As the forward finger is elevated, the rearward finger is lowered to prevent the next vial on the shelf from rolling forward. If for any reason the gates are prevented from being oscillated by improper engagement with a vial, spring 111 will yield and take up pressure which would otherwise crush the vial.

15 The platen 91 is connected to extension 104 by the swivel connection shown in Figs. 8 and 9. It will be seen that a swivel block 118 having a stub shaft 119 integral therewith is journaled in extension 104 for pivotal movement about a horizontal axis. The swivel block is apertured to receive a pin 121 at the upper end of the platen so that the latter is free to turn about a vertical axis. By so swiveling the platen, it adjusts itself to irregularities in the vial and properly engages the vials to rotate them as will be explained later. The platen is normally urged in the direction of roll 47 by spring 122 connected at one end to the platen and at its other end to an adjustable arm 123 which may be 20 swung about its fulcrum to vary the tension of the spring. Extension 104 may also be adjusted longitudinally with respect to lever 105 by means of a pin and slot connection indicated at 124.

As will be seen from Figs. 3 and 11, the forward or vial engaging face 125 of the platen is 30 concave so that the surface of the vial engaged by the platen is limited to substantially line contact by the edges of the platen. A suitable cover 126 of leather, rubber or similar material for the platen provides sufficient friction to enable the platen to roll the vial over the printing roll as the platen is lowered, it being understood that the platen engages the vial and urges it with some degree of pressure into contact with the printing roll. It is also obvious that cylindrical objects having a length less than the width of the platen will be so engaged by the concave face of the platen that only the ends of the objects touch the platen. Here, also, there is only line contact, the longitudinal side surfaces of the object being spaced from the platen. Smearing of the transferred ink is thus inhibited.

45 Adjustably fixed to the housing 51 is an abutment comprising a roller 127 on the laterally projecting rod 128 suitably secured to a block 129. The latter is slidably supported on a plurality of rods 131 and its position thereon may be adjusted by means of an adjusting screw 132. Intermediate the lower end of the platen and its swivel is a cam piece 133 which projects beyond the forward face of the platen and which strikes roller 127 when the platen is near the lower extremity of its vertical reciprocation to move the platen out of engagement with the vial. This camming action occurs after the design has been transferred to the vial and permits the vial to drop into a receptacle 134 to which further reference will be made hereinafter.

50 As will be seen in Figs. 2 and 7, the forward end of the shelf 93 is provided with a pivoted extension 135 normally held in alignment with the shelf by a spring hinge 136 with its forward edge in proximity to the roll 47. It will be evident, however, that the extension will yield when 55 struck by the descending platen to permit the

platen not only to be lowered but also to be swung away from the vial being printed as the cam 133 strikes roller 127. As the platen is elevated, the extension is again swung upwardly into alignment with shelf 93.

Suitably secured to the base of the machine in underlying relation to the printing mechanism are a pair of horizontally disposed brackets 131, 138, in which are journaled shafts 139 having fast thereon a series of conveyor drums 141, and shaft 142 to which is fixed drive sprocket 143. Also secured to shafts 139 are sprockets 144 while sprocket 145 is fixed to shaft 142. It will be seen that the diameters of sprockets 144 are less than that of sprocket 145. Chain 146 engages all of the sprockets 144, 145, so that they rotate in timed relation to each other.

The means for driving the conveyor comprises a link 147 connected at one end to lever 113 and at its other to pawl 148 arranged to intermittently rotate shaft 142 by means of a ratchet 149 thereon. Thus with each reciprocation of the platen 91 the sprockets are turned through a predetermined angle.

Each of the trays 134 comprises a plurality of transverse contiguous pockets or compartments 151, the bottoms of which are formed from perforate or reticulate material 152 to provide for passage of air therethrough. Further, the bottoms are concave, as shown in section in Figs. 4 and 10, so that a cylindrical article lying thereon is supported by the bottom only at the ends of the article, as illustrated by the vial shown in dotted lines in Fig. 4. The tray pockets are made up of curved transverse dividing walls 153 and ends 154. The ends of the pockets are connected to a pair of parallel side plates 155 each of which is bent outwardly and then downwardly, as shown in Fig. 12. The bottom edge is then folded upon itself so that an inverted L-shaped flange having a reinforced lower edge is provided along each side of the tray. The lateral portion of these flanges is provided with spaced perforations 156 to form a rack engageable with sprocket 143. It is to be noted that the perforations are spaced a distance equal to that between the pockets and that sprocket 143 turns through an angle with each intermittent movement thereof sufficient to move the tray a distance corresponding to that between the centers of two adjacent pockets.

As will be seen in Fig. 4, drums 141 have a relatively smooth cylindrical surface upon which the lower turned edges of the side plates rest. Flanges 157 on the drums prevent lateral displacement of the trays during their travel over the conveyor. While the surface of the drums is smooth, there is sufficient friction between the lower edges of the trays and the drums to move the trays upon rotation of the drums. Thus the trays are carried toward sprocket 143 by the drums until the teeth of sprocket 143 engage the rack portion of the tray sides. The tray is then given a step-by-step movement corresponding to the distance between the pockets of the trays. As stated hereinbefore, sprockets 144 are smaller than sprocket 145. Hence their angular velocity is greater than that of the drive sprocket 143. Trays carried by drums 141 will therefore move more rapidly than a tray being moved by sprocket 143. This arrangement permits the machine operator to place empty trays on the drums without regard to the spacing therebetween. At the same time the empty trays on the drums, moving a greater distance than one engaged by the

drive sprocket, will "catch up" with the tray immediately under the platen. In this way successive trays are brought into end abutting relation and a pocket is always disposed beneath the platen. Since the surface of the drums is smooth, relative sliding movement between the drums and tray which has caught up with another being driven by the sprocket is permitted.

Mounted on bracket 137 are a pair of parallel rails 158, 158' spaced a distance substantially equal to that between the lower edges of the tray sides. Rail 158' is somewhat shorter than rail 158 to permit engagement of the drive sprocket with the tray. The rails support the trays and permit sliding movement thereof until they are removed by the machine operator. To prevent elevation of the tray while it is in engagement with the drive sprocket a yieldable abutment 159, shown in Fig. 12, is attached to the bracket and overlies the rack portion of the tray near the drive sprocket.

It is sometimes necessary to adjust the various transfer rollers to insure proper contact thereof with the inking rollers. In Fig. 2 is illustrated means by which the yoke 55 may be adjusted, these means comprising a pair of screws 161, 161' abutting a projection 162 on sleeve 163, the latter being fixed to shaft 56. By loosening one screw and tightening the other, proper contact of the rolls may be effected. In Figs. 13 and 14 is shown adjusting means for varying the relation of individual rolls with respect to the yoke. In this form of adjustment a plurality of screws 164 threaded in a boss 165 on the yoke bear against the roll shaft. It is evident that the eccentricity of the shaft axis may be varied by proper displacement of the screws so that the roll can be positioned to insure the desired contact of the roll with other rolls in the inking mechanism.

The operation of the machine will be apparent from the foregoing description thereof. Ink is supplied to the dies by the several inking rollers and the design, lettering, or other impression transferred to the large printing roll. As a vial is released and permitted to roll into engagement with the printing roll, the platen is lowered and urged into engagement with the vial, sufficient pressure being imposed on the vial to insure transfer of the design from the printing roll to the vial. At the same time the platen descends at such speed that rotation of the vial by the printing roll is permitted to provide for rolling contact therebetween without slippage. In this way the design is transferred without smearing of the ink. Further, the platen, having a concave face, engages only a narrow circumferential portion of the vial adjacent its ends so that not only is smearing obviated, but it is evident that the design may extend circumferentially around the vial substantially through 360°. The platen is then cammed away from the vial, permitting the latter to drop into one of the tray compartments. The trays are moved intermittently and in such timed relation to the operation of the printing roll and platen that an empty compartment is presented beneath the platen with each descent thereof. The concave perforate bottoms of the trays insure proper support of the vials after the design has been printed thereon, there being no possibility of contact between the bottom and that portion of the vial having the design thereon. Since free passage of air through the bottom hastens drying of the ink, it is apparent

that the combined printing and drying operations are expedited.

While a preferred form of the invention has been illustrated and described, it is not intended that the invention be limited to the precise arrangement of parts, but is to be construed broadly within the meaning of the appended claims.

Having described my invention, what I claim and desire to secure by Letters Patent is:

1. In a machine for printing on cylindrical objects, a rotatable printing roll, a platen for urging the objects into engagement with said roll, said platen being concave in transverse cross section to form an object-contacting face, said face being arcuate from one longitudinal edge of the platen to the other longitudinal edge thereof, means for rotating said roll, and means for effecting longitudinal reciprocation of said platen.

2. In a machine for printing on cylindrical objects, a rotatable printing roll, a platen for urging the objects into engagement with said roll, means for rotating said roll, means for effecting longitudinal reciprocation of said platen, and a swivel connection between one end of said platen and the means for reciprocating the platen, said connection being pivoted on two axes, one of said axes being parallel to said printing roll, the other axis being parallel to the longitudinal edges of said platen.

3. In a machine for printing on cylindrical objects, a rotatable printing roll, a platen for urging the objects into engagement with said roll, said platen being concave in transverse cross section to form an object-contacting face, said face being arcuate from one longitudinal edge of the platen to the other longitudinal edge thereof, means for rotating said roll, means for effecting longitudinal reciprocation of said platen, and a swivel connection between one end of said platen and the means for reciprocating the platen, said connection being pivoted on two axes, one of said axes being parallel to said printing roll, the other axis being parallel to the longitudinal edges of said platen.

4. In a machine for printing on cylindrical objects, a rotatable printing roll, a platen for urging the objects into engagement with said roll, means for rotating said roll, means for effecting longitudinal reciprocation of said platen, and means for swiveling one end of said platen to said platen reciprocating means including two pivotal connections having their axes perpendicular to each other, one of said axes being parallel to said printing roll, the other axis being parallel to the longitudinal edges of said platen.

LUIGI MARZOCCHI.
